UNITED STATES PATENT OFFICE.

WILLIAM EARL GRAHAM, OF GARY, INDIANA, ASSIGNOR OF ONE-HALF TO ALEX. N. ORPHAN, OF GARY, INDIANA.

MIXING DEVICE.

Application filed December 9, 1922, Serial No. 605,918. Renewed December 10, 1923.

To all whom it may concern:

Be it known that I, WILLIAM E. GRAHAM, a citizen of the United States, residing at Gary, in the county of Lake and State of Indiana, have invented new and useful Improvements in Mixing Devices, of which the following is a specification.

This invention relates to mixing devices and has for its object the provision of a novel device designed primarily for use at soda fountains and the like, though not necessarily confined to such use, for the purpose of mixing malted milk, egg or similar drinks, milk shakes and the like.

An important object is the provision of a device of this character which combines in one machine three machines either of which may be used alone, any two of which may be used or all of which may be used simultaneously, the device in this way combining the advantages of three separate ordinary devices while taking up less room on the fountain or counter.

Another object is the provision of a device of this character which is provided with an electric motor which furnishes the power and which has clutch controlled drive connections with the various mixing elements, the clutch means being so constructed that it automatically operates control switches for applying power to the motor or cutting off the power as the case may be.

An additional object is the provision of a device of this character which will be simple and inexpensive in manufacture, neat and attractive in appearance, rapid in action, efficient and durable in service and a general improvement in the art.

With the above and other objects and advantages in view the invention consists in the details of construction to be hereinafter more fully described and claimed and illustrated in the accompanying drawings, in which:

Figure 1 is an elevation of the device, Figure 2 is a vertical section taken in a plane parallel with the front,

Figure 3 is a vertical section taken at right angles to Figure 2,

Figure 4 is a horizontal section, Figure 5 is a vertical section similar to Figure 3 but taken at the opposite of the standard,

Figure 6 is a diagram of the electric circuit and

Figure 7 is a detail sectional view on the line 7—7 of Figure 4.

Referring more particularly to the drawings I have shown my device as comprising a hollow standard 10 rising from a suitable base 11 and carrying a casing 12 within which is mounted all the transmission mechanism to be described.

Vertically adjustably mounted upon the standard 10 is a bracket 13 carrying a platform 14 designed to support a glass or other receptacle containing a mixture to be agitated or shaken by one of the elements of the device. Extending from the opposite side of the standard is a guide 15 against which may be placed a receptacle of mixture to be stirred by another element of the device and depending from one end of the casing 12 is an arm 16 provided with a guide 17 similar to the guide 15 and against which may be placed a receptacle containing a mixture to be stirred by the remaining mixing element to be described.

On the standard 10 and arm 16 are clips 19^a for engagement over the edge of a glass or other receptacle used for preventing overturning thereof.

Suitably mounted within the casing 12 is an electric motor 18 of any preferred type and of any necessary power and the lead wires 19 to this motor are brought down through the hollow standard 10 for the purpose of convenience. The motor shaft 20 is prolonged so as to extend along the major portion of the casing 12 longitudinally thereof at substantially its center and secured upon one end of this shaft is a small friction disk 21 while secured to the other end are two spaced similar disks 22 and 23.

Located within this portion of the casing 12 which overlies the platform 14 is a partition or bearing portion 24 through which is rotatably and slidably mounted a shaft 25 upon the lower end of which is journaled a friction disk 26 disposed below and designed to co-operate with the disk 21. Carried by and journaled through this disk 26 is a depending spindle 27 which has its lower end carrying a beater 28 and which has its upper end carrying a spur pinion 29 meshing with a similar pinion 30 which is

rigidly secured on the underside of the partition 24. The bottom of the casing overlying the platform 14 must be partly open so as to permit the rotary as well as spinning 5 action of the spindle 27 as will be obvious.

Mounted within this end portion of the casing is a bearing bracket 36 through which is journaled a stem 31 which has its forward end projecting beyond the casing and 10 carrying a control knob 32. Beneath this stem is a block member 33 carried by the upper end of the shaft 25. Encircling the shaft 25 is a coil spring 34 which abuts against a member 33 and against a sleeve 15 bearing 35 through which the shaft 25 passes. Secured on the stem 31 is a cam 36 engaging the member 33 so that when the knob 32 is turned to the left the member 33 will be forced downwardly against the resistance 20 of the spring 34 carrying with it the disk 26 and beater structure carried thereby so that engagement between the disks 21 and 26 will be broken.

Located in the other end portion of the 23 casing and rising from the bottom thereof are bearings 37 and 38 within which are rotatable bushings 39 and 40 within which again are eccentrically journaled depending stems 41 and 42 which are similar. These 30 stems project downwardly to a considerable extent below the casing and have their lower ends carrying whirling disks 43 and 44, respectively, designed to be received within receptacles disposed against the guides 15 or 17 respectively. The bushings 39 and 40 carry arms 45 and 46. Secured upon the upper ends of the stems 41 and 42 are friction disks 49 and 48 adapted to bear against the disks 22 and 23 respectively and it will 40 be observed that the bushings are cut away at one side to accommodate these small friction disks.

Journalled through the front of the casing are stems 51 and 52 carrying operating 45 knobs 53 and 54 and also carrying cams 55 and 56 respectively engageable with the arms 45 and 46 whereby to rock the bushings to a sufficient extent to bring the disks 49 and 48 into engagement with the associated 50 disks 22 and 23.

I provide a control switch device associated with each of the stems 31, 51 and 52 and each of these switch devices consists of a supporting block 57 of insulating material carrying a stationary contact 58 with which is engageable a movable contact 59. All the contacts 58 are connected with one of the wires leading to the motor while each of the contacts 59 is connected 60 with one terminal of the motor, the other terminal of the motor being connected directly to the power line as shown in the diagram. In other words these three switch devices are in parallel. The stem 31 carries a cam 60 which engages the contact 59 of the

associated switch for closing the circuit to the motor when the knob 32 is turned to bring the disk 26 into engagement with the drive disk 21. The stems 51 and 52 carry cams 61 and 62, respectively, which are engageable with the contacts 59 of the associated switch devices when the knobs 53 and 54 are turned to throw the disks 49 and 50 into engagement with the disks 22 and 23. 70

In the operation it will be seen that a 75 glass or other receptacle containing ingredients to be mixed may be placed upon the platform 14 in such a way that the beater 28 will be within the glass. By then turning the knob 32 to the right, the disk 26 will 80 be engaged with the disk 21 and the motor will be energized so that the beater 28 will operate to mix the materials.

In a similar manner, receptacles containing 85 mixtures may be placed beneath the spindles 41 and 42 against the guides 15 and 17 and the knobs 53 and 54 turned to the right to engage the disks 49 and 50 and to close the circuit through the motor. The 90 rotation of the disks 43 and 44 carried by the spindles 41 and 42 will operate to mix together the materials. It will be noted that either one of the mixing devices may be used alone, any two may be used at the same time or all may be operated simultaneously. 95 The device thus operates to combine in one apparatus the functions of three and consequently saves space on a counter or soda fountain. Owing to the automatic making and breaking of the control circuit when the 100 operating knob is turned to throw in either one of the mixing devices it is apparent that the operation and control is greatly simplified and that auxiliary switches will be entirely unnecessary, while at the same time 105 waste of current will be prevented.

While I have shown and described the preferred embodiment of the invention it is of course to be understood that I reserve the right to make such changes in the form, construction and arrangement of parts as will not depart from the spirit of the invention or the scope of the subjoined claims. 110

I claim:

1. A mixing machine comprising a stand- 115 ard supporting a casing, power means within the casing for driving a shaft disposed therein, a plurality of vertically depending spindles journaled through the bottom of the casing and carrying spinner disks, and 120 selectively operable clutch means for driving either or all of said spindles from said shaft, and operating knobs located on the front of the casing and having stems extending thereinto and carrying clutch control means, said power device being electrically operated, and a plurality of circuit closers arranged in parallel and connected in the circuit to said drive device, and means carried by said 125 stems for operating said circuit closers auto- 130

matically when the stems are moved to engage the clutch devices.

2. A mixing machine comprising a standard supporting a casing, power means within the casing for driving a shaft disposed therein, a plurality of vertically depending spindles journaled through the bottom of the casing and carrying spinner disks, and selectively operable clutch means for driving either or all of said spindles from said shaft, operating knobs located on the front of the casing and having stems extending thereinto and carrying clutch control means, said power device being electrically operated, and a plurality of circuit closers arranged in parallel and connected in the circuit to said drive device, and means carried by said stems for operating said circuit closers automatically when the stems are moved to engage the clutch devices, each circuit closer consisting of a stationary contact and a spring contact, and the operating means therefor consisting of cams on said stems engaging the spring contacts.
3. In a mixing machine, a standard, a casing supported thereon, an electric motor within the casing having its shaft extending throughout the major portion thereof and carrying a plurality of friction disks, a plurality of spindles vertically journaled through the bottom of and depending below the casing and equipped with agitating elements, a series of control knobs located on the front of the casing, friction disks carried by said spindles, and cam operated clutch means moved by said knobs for connecting or disconnecting the associated disk members.
4. In a mixing machine, a standard, a casing supported thereon, a motor within the casing hav-

ing its shaft provided with a plurality of friction disks, vertically depending spindles journaled through the bottom of the casing and carrying agitator elements, friction disks carried on said spindles and located adjacent said first named disks, housings surrounded and forming bearings for the upper ends of the spindles, bearings within the casing within which said housings are eccentrically mounted, arms projecting from the housings, operating knobs at the front of the casing mounted upon stems extending thereinto, and cams on said stems engageable with said arms to rock the housings whereby to bring the associated disk members into engagement.

5. In a mixing machine, a standard, a casing supported thereon, a motor within the casing having its shaft provided with a plurality of friction disks, vertically depending spindles journaled through the bottom of the casing and carrying agitator elements, friction disks carried on said spindles and located adjacent said first named disks, housings surrounded and forming bearings for the upper ends of the spindles, bearings within the casing within which said housings are eccentrically mounted, arms projecting from the housings, operating knobs at the front of the casing mounted upon stems extending thereinto, and cams on said stems engageable with said arms to rock the housings whereby to bring the associated disk members into engagement, and a circuit closer associated with each knob and all connected in parallel in the motor circuit, and means on the stems for controlling the circuit closers.

In testimony whereof I affix my signature.
WILLIAM EARL GRAHAM.
